UNITED STATES PATENT OFFICE.

FREDERICK A. C. KAISER, OF HOBOKEN, NEW JERSEY, ASSIGNOR TO THE AMERICAN LITHOGRAPHIC COMPANY, OF NEW YORK, N. Y.

DESIGN FOR A BOX.

SPECIFICATION forming part of Design No. 29,274, dated August 30, 1898.

Application filed June 28, 1898. Serial No. 684,692. Term of patent 7 years.

To all whom it may concern:

Be it known that I, FREDERICK A. C. KAISER, a citizen of the United States, residing at Hoboken, in the county of Hudson and State of 5 New Jersey, have invented a Design for a Box; and I do declare the following to be a full, clear, and exact description, such as will enable others skilled in the art to which it appertains to make and use the same.

10 My design is for a box.

In the accompanying drawing the design is shown in the lid or cover of the box, the view being a front elevation with the lid raised.

15 The design comprises the figure of a man holding a staff in one hand, while with the other hand is presented to view a written

declaration. To the staff is attached a flag which floats behind the figure and forms a background therefor. Below the figure is a panel containing a chart of an island, and 20 perched above the panel is the figure of an eagle with spread wings.

I claim—

25 The design for a box substantially as shown and described.

In testimony whereof I affix my signature in presence of two witnesses.

FREDERICK A. C. KAISER.
